US00D456352S

(12) **United States Design Patent** (10) Patent No.: **US D456,352 S**
Germagian et al. (45) Date of Patent: **** Apr. 30, 2002**

(54) **UNINTERRUPTIBLE POWER SUPPLY**

(75) Inventors: **Mark H. Germagian**, Hudson;
Benjamin J. Beck, Boston, both of MA
(US)

(73) Assignee: **American Power Conversion**, West
Kingston, RI (US)

(**) Term: **14 Years**

(21) Appl. No.: **29/110,505**

(22) Filed: **Sep. 8, 1999**

(51) LOC (7) Cl. **13-02**

(52) U.S. Cl. **D13/110; D13/123**

(58) Field of Search **D13/110, 123;
307/64, 66, 150, 340/636**

U.S. patent application No. 09/392,129 filed Sep. 08, 1999
Germagian.

Primary Examiner—Joel Sincavage

(74) Attorney, Agent, or Firm—Mintz, Levin, Cohn, Ferris,
Glovsky & Popeo, P.C.

(57) **CLAIM**

We claim the ornamental design for an uninterruptible power supply, as shown and described.

DESCRIPTION

FIG. 1 is a front and upper left perspective view of an uninterruptable power supply in accordance with the present invention;

FIG. 2 is a rear and upper left perspective view of the uninterruptable power supply of FIG. 1;

FIG. 3 is a front view of the uninterruptible power supply of FIG. 1;

FIG. 4 is a back view of the uninterruptible power supply of FIG. 1;

FIG. 5 is a top view of the uninterruptible power supply of FIG. 1;

FIG. 6 is a bottom view of the uninterruptible power supply of FIG. 1; and,

FIG. 7 is a right side view of the uninterruptible power supply of FIG. 1.

Any broken line illustrations in the drawings are not part of the claimed design.
